[57] ABSTRACT

A flat paint brush is guided in a device which comprises a base plate and a guide plate pivotally mounted on the base plate for pivoting parallel to the brush plane. The base and guide plates are interconnected by a pivot pin. One end of the pivot pin is rectangular and frictionally engaged in a like opening in the guide plate while the other pivot pin is oval and frictionally engaged in a like oval slot portion in the base plate, which slot portion extends from the outer edge of the base plate, with an elongated slot portion extending upwardly therefrom. A cover plate larger than the pivot ends is mounted over each end.

DEVICE FOR GUIDING A FLAT PAINT BRUSH

The present invention relates to improvements of the painting device disclosed and claimed in our U.S. Pat. No. 3,401,418, dated Sept. 17, 1968, whose disclosure is incorporated herein as part of the present disclosure to avoid redundancy.

In the patent, we have disclosed a device for painting areas with a flat paint brush extending in a plane and having an axis and a paint-applying end portion perpendicular to this axis. This device includes a base plate forming part of a brush guide and a guide plate having an outer edge normally perpendicular to the paint brush axis. The guide plate is spaced from the base plate and a pivot pin pivotally mounts the guide plate on the base plate for pivoting parallel to the brush plane. The brush guide including the base plate may be of one piece and comprises a trough-shaped portion receiving a spring, the guide plate having an inner edge extending into the trough-shaped portion, and the spring ends abutting the inner guide plate edge and a shoulder in the trough-shaped portion, respectively. The brush guide further comprises a clamp for clamping the guide to a handle for the brush. The guide plate preferably is more or less semi-circular.

Painting is effected with this device by guiding the outer edge of the guide plate along a ruler or an edge of the area to be painted and simultaneously pressing the paint-applying end portion of the brush against this area. This causes the outer edge of the guide plate to be retracted against the spring bias so that the brush can apply paint to the area. However, it has been found that, during the operation of such a device, paint penetrates to the spring and, after the paint dries on the spring, it affects its elasticity so that retraction of the guide plate will be inhibited. After a while, therefore, the device becomes useless.

It is the primary object of this invention to obviate this disadvantage and to enable the guide plate to retract resiliently without the use of a spring in the open trough-shaped portion of the base plate.

This object is accomplished according to the invention by providing a base plate which defines a slot means consisting of an initial oval portion adjacent the outer edge thereof and an elongated slot portion extending inwardly from the oval portion, and a guide plate defining a polygonal opening in register with the oval slot means portion. The synthetic resin pivot pin has one end of oval cross section generally conforming to the oval slot means portion and frictionally engaged therein, and another end of polygonal cross section generally conforming to the polygonal opening and frictionally engaged therein. A cover plate extending beyond the circumferences of the pivot ends is mounted over each pivot pin end.

If desired, the brush holder or handle and the base plate, including its trough-shaped portion, clamp and an operating lug, may be produced of synthetic resin in one piece.

This journaling of the pivot pin causes the guide plate to be resiliently retracted upon pivoting and/or pressure, the oval end of the pivot tending to return to its original position in the conforming oval slot means portion.

The above and other objects and advantages of the present invention will become more apparent from the following detailed description of a now preferred em-

bodiment thereof, taken in conjunction with the accompanying drawing wherein

FIG. 1 is a top elevational view of the paint brush guiding device, without the pivot pin;

FIG. 2 is a longitudinal section through the base plate of the device;

FIG. 3 is a side elevational view of the pivot pin;

FIG. 4 is a section along line IV-IV of FIG. 3.

FIG. 5 is a section along line V-V of FIG. 1 including the pivot pin.

Referring now to the drawing, the base portion 13 of the paint brush guiding device is shown to have a resilient clamp 18 so that the device may be snapped onto a handle for the paint brush. As more particularly shown and explained in our above-mentioned patent, this portion comprises a base plate or guide plate carrier 16 whence extends a trough-shaped portion 17. The clamp 18 projects from the end of the trough-shaped portion and an operating lug 19 projects oppositely thereto to enable the guide to be readily moved, all as explained fully in our patent.

According to this invention, the base plate 16 defines a slot means consisting of an initial oval opening portion 23 adjacent the outer edge 27 of the base plate and an elongated slot portion 22 extending inwardly from the oval portion a concentric, but larger, undercut 26 subtends opening 23. In operation, the brush guiding device is so mounted in respect of the brush that the slot means extends parallel to the brush axis, the outer edge 27 extending perpendicularly thereto.

The guide plate 12 is substantially parallel to, and spaced from, the base plate 16 and defines a polygonal opening 11 in register with the oval slot means portion 23, the illustrated opening being rectangular.

Pivot pin 14, of synthetic resin, mounts the guide plate 12 on base plate 16 for pivoting parallel to the base plate, the outer edge 21 of the guide plate extending usually perpendicularly to the brush axis and beyond the outer edge 27 of the base plate. The pivot pin 40 has one end 24 of oval cross section generally conforming to the oval slot means portion 23 and frictionally engaged therein, while the other pivot pin end 25 is of polygonal cross section generally conforming to the polygonal opening 11 and frictionally engaged therein.

Cover plates 28 and 29 extending beyond the circumferences of the pivot ends are mounted on the respective pivot pin ends, the diameter of cover plate 28 being such that it may pass through the polygonal opening 11.

In assembling the device in the manner shown in FIG. 5, the pivot pin 14 is passed through the polygonal opening 11 of the guide plate 12 and the pivot pin end 25 is frictionally engaged with the opening 11 so as to fix the pivot pin to the guide plate. The oval pivot pin end 24 is now pressed into the oval slot means portion 23 of the base plate 16 whereby the guide and base plates are interconnected.

When pressure is exerted upon the outer edge 21 of the guide plate to cause pivoting thereof, the oval pivot pin end 24 is turned in its oval slot means 23 to widen the same, this widening being made possible by the slot 22 extending from 23. As soon as this pressure is terminated, the resiliency of slot means 22, 23 immediately causes the oval pivot pin end 24 to return to its original position. No other spring means is accordingly required to keep the guide plate in its normal position and/or to enable it to be retracted.

We claim:

1. A device for guiding a flat paint brush, comprising
  1. a base plate having an outer edge, the base plate defining a slot means consisting of
    - a. an initial oval portion adjacent the outer edge and
    - b. an elongated slot portion extending inwardly from the oval portion;
  2. a guide plate substantially parallel to, and spaced from, the base plate and defining a polygonal opening in register with the oval slot means portion;
  3. a pivot pin of synthetic resin for pivotally mounting the guide plate on the base plate for pivoting parallel to the base plate, the pivot pin having two ends,

- a. one of the pivot pin ends being of oval cross section generally conforming to the oval slot means portion and frictionally engaged therein, and
- b. the other pivot end being of polygonal cross section generally conforming to the polygonal cross section frictionally engaged therein; and
4. a cover plate extending beyond the circumferences of the pivot ends mounted over each of said ends.

2. The device of claim 1, wherein the base plate is of synthetic resin and is integral with a trough-shaped portion extending therefrom, a clamp on the trough-shaped portion, and an operating lug on the base plate projecting oppositely to the clamp.
